UNITED STATES PATENT OFFICE.

EZRA NICHOLSON, OF CLEVELAND, OHIO.

HOISTING AND CONVEYING MACHINE.

SPECIFICATION forming part of Letters Patent No. 433,805, dated August 5, 1890.

Application filed October 15, 1888. Serial No. 283,187. (No model.)

To all whom it may concern:

Be it known that I, EZRA NICHOLSON, a citizen of the United States, residing at Cleveland, in the county of Cuyahoga and State of Ohio, have invented certain new and useful Improvements in Electric Hoisting and Conveying Machines, of which the following is a specification.

This invention relates to hoisting and conveying machinery, principally adapted for elevating and conveying coal and ore or other material from vessels, &c., in which is provided a bridge-tramway having a hinged extension arranged to be adjusted over the hold and hatchways of a vessel or over mines, and a tram-car provided with an electric or other motor for lowering and raising a bucket or for propelling the car as required, also provided with a weighing mechanism for weighing the bucket and contents.

The object of my invention is to facilitate the work of such machines and reduce the labor of operating them, to accomplish which I construct a tramway and tram-car substantially as illustrated in the accompanying drawings, in which—

Figure 1 is a side elevation of a tramway and a tram-car embodying my improvements. Fig. 2 is a front or end elevation of the tramway. Fig. 3 is a top or plan view of the drop-hinged extension. Fig. 4 is a side elevation of the tram-car with parts broken away, showing the motor mechanism and the scale-beam weighing mechanism. Fig. 5 is a top or plan view of the same, having some portions omitted or broken away to show the said mechanism. Fig. 6 is a view of the upper part of the tram-car frame-work, transversely seen from that of Fig. 4, to show the construction of the hoisting-sheave and its connection with the weighing mechanism. Fig. 7 is a detached perspective view of the yoke and hook mechanism for catching and holding the sheave. Fig. 8 is a top or plan view of the bridge-tramway. Fig. 9 is a shifting mechanism, partly in section, on line 9 of Fig. 5, and looking in the direction of the arrow, for transferring the power of the motor from propelling to the bucket raising and lowering mechanism, and vice versa. Fig. 10 is an end view of tram-car, showing the motor mechanism and method

of connecting same to electric conducting-wire. Fig. 11 is an enlarged view of the foot of trestle B, showing roller and means of propelling the trestle for shifting the position of same, showing the driving-pulley attached to a lever-frame and a hand-lever, whereby said pulley is moved for changing its power from one mechanism to the other.

Description of tramway.—A represents a bridge-tramway consisting of parallel rails firmly joined together by cross bars and braces. The front end is supported by a vertical trestle B, having suitable base provided with rollers B^x for shifting the tramway laterally. The rear and central portions of the tramway are supported upon suitable trestles B' and C, having suitable tracks C^x for shifting the tramway thereupon. Upon the said trestle C is provided a transverse tramway C', against which the rear ends of the bridge-tramways abut. The transverse tramway C' is a little lower than bridge-tramways, and is provided with a suitable truck C², upon which the tram-cars may be run for transferring them from one tramway to another. To enable the bridge-tramways to be easily shifted, they are provided with wheels or rollers running on the tracks on the trestles, and the rollers are connected with gear c and pinion c² on a crank-shaft c³, by which the tramways are easily propelled. To the forward end of the bridge-tramway A is hinged an extension D, supported by suitable guys D'. This extension is made partly open and partly strengthened by cross-pieces and braces, the open portion being made to enable the bucket to be lowered through to the hold of a vessel lying below. Through the bridge-tramway are also made openings for the same purpose. The bucket on the tram-car being raised above the tramway allows the tramway to be built with cross-pieces and braces, thus enabling it to be made cheaper, simpler, and stronger than those which do not raise the bucket above the surface of the tramway. By the side of the track or at any other suitable part of the tramway is provided a trough or suitable conduit E for holding or supporting an electric conducting-wire e, and to the car is attached an arm or lever e², having a roller on its lower end, which rides upon the said elec-

tric wire and is used for conducting electricity to the motor on the car. The extension D is raised and lowered by means of ropes *b*, sheaves *a a*, and a windlass *d*.

5 *Description of tram-car.*—A suitable frame F, preferably made of angle-iron, is provided, having wheels *f f*, with axles *f²* set in boxes or bearings attached to the frame and arranged to run on the track-rails on the bridge-tramways. This frame is left entirely open in its middle part for the purpose of enabling the bucket G, which it carries, to be raised and lowered therethrough. On one end of said frame F is supported the motor mechanism, adapted to either propel the car back and forth on the tramway or for raising and lowering the bucket. In Fig. 4 an electric motor H is shown secured to the frame by any suitable means. The driving-shaft *h* of said motor has a friction-wheel *h²*, from which power is transmitted operating the other machinery. One end of the shaft *h* of said motor is supported in a hanger *i*, Fig. 9, pivotally suspended from lever I, which is also 20 pivotally attached to one end of the frame F. The other and moving end of said lever I is pivotally attached to a short hanging arm *j*, suspended from a lug *j²* on an upright lever J. This lever J has its fulcrum on a pin *k* 25 on the frame F, below the said lug *j²*, and to its lower end is pivotally attached a connecting-rod K, connecting it with the hanger *i* at its junetion with the shaft *h*. The lever J extends upward and is operated by a man who 30 rides upon the car and controls all the movements of the several mechanisms on the car. L is a shaft parallel with the motor-shaft *h*, and supported in a suitable bearing on the frame F, and carries a friction-wheel Z and 35 a toothed pinion *Z²*, which pinion meshes with a gear-wheel *m* on one of the axles *f²*. When it is desired to move the car, the operator throws the friction-wheel *h²* into contact with the friction-wheel Z. M is a third 40 shaft parallel with shaft *h*, and carries a friction-wheel N and a toothed pinion *n*. O is a fourth parallel shaft situated above the shaft *h*, and carries a drum *O²*, having a gear *O³* meshing with the aforesaid pinion *n*. These 45 shafts have suitable bearings in the side frame-work. The drum is operated when desired by the operator throwing the friction-wheel *h³* into contact with the friction-wheel N. Over this mechanism is placed a floor 50 upon which the operator stands, and it may be inclosed to protect it from intrusion without. A brake is placed on one end of the drum, consisting of a band composed of blocks P P linked together, and arranged to bind 55 upon the rim of the drum for checking or stopping its motion when desired. This brake is operated by means of a foot-lever *p* by the operator, which closes and binds the link-band on the rim of the drum. 60 At the top of a triangular frame standing on the car-frame F is provided a sheave and sheave-grappling device and a scale-beam or

weighing mechanism, as follows: To the side frames are secured a ridge-bar R, Fig. 6, and two lower bars R², connecting the two sides. 70 Upon the two lower bars are supported two cross-bars Q Q, projecting forward and back. Upon the forward ends is provided a large pulley-wheel Q², over which a rope R³ from the drum passes, thence to and through a sheave S, and having its end fastened at the rear end of said cross-bars Q Q. The sheave S has a hook to which is hung the bail of the bucket. U is a yoke having an eye or loop by which it is suspended on the end of a balance-bar V, fulcrumed in a hanger V², attached to ridge-bar R, one end of which is connected with scale-beam W. The lower parts of the yoke are narrowed and pointed, as seen in Fig. 7. T T are two bars, the upper ends of which are attached to the sides of the head of the yoke U, being provided with holes for suspending them on the projecting ends of a stout pin *u*, inserted through the head of the yoke. The lower ends of said bars T T are made in the form of hooks *t t*. This yoke and hooked-bar mechanism hangs between the two cross-bars Q Q, and is designed for catching and holding the bucket when desired. This is done by letting the 90 hoisting-rope draw the bucket up so that the sheave S will pass up into the yoke, when its projecting-pin *s* will spread the yoke-points and the bar-points until it passes above the hooks *t* on the bars T. Then the hooks close in again and the rope may be slackened up, and the bucket will hang suspended on the hooks. A spring *s^x* is attached between the bars T T and the yoke for drawing them together. *y* is a spring-hook attached to the frame of car 100 for holding the bars T T open from the yoke when desired. X is a bell-crank attached to the car-frame, the upper arm of which is connected by a cord to the bars T T, and its other arm is connected by a cord with a foot-lever X². This is designed for use by the operator for pulling the bars T T and opening the catch-yoke and releasing the bucket therefrom. A wedge *y³* is provided for inserting under the pin *u*, for supporting the yoke upon the cross-bars Q Q, to relieve the scale-beam from the 110 weight of the bucket and contents when the scale-beam is not in use. The engine-house and dynamo for generating the electricity for the motors on these 120 cars may be located at any suitable place or distance and the electricity conveyed therefrom by wires to the points of use. The operations of these mechanisms are performed by the man on the car in manner as follows: 125 To move the car the lever J is thrown over to bring the motor friction-pinion *h²* in contact with the friction-wheel *l*. The operator may by this means propel the car at pleasure back and forth on the tramway. When the 130 car is moved over a vessel or other place, the bucket may be lowered for filling or dumping by its own gravity, first drawing back the yoke U by pressing on the foot-lever X² and

slackening the brake on the drum. It is again raised by throwing the motor friction-pinion over against the friction-wheel N, which operates the drum and thus hauls up the bucket.

5 Then the bucket being raised above the level of the tramway the motive power may be applied for moving the car, and when it has arrived at the required place the bucket may be lowered and its contents dumped, or it may 10 be dumped without lowering. Should the operator desire to weigh the bucket and contents, he withdraws the wedge y³. This lets the yoke U hang suspended from the balance-bar V. He then lets the sheave S rise up and 15 catch into the hooks on the bars I I. The bucket hangs suspended from the yoke, and the exact weight of the load may be ascertained with the scale-beam W. Then the rope may be again hauled up tight, relieving the 20 beam V of its weight, the wedge returned to place, and by pressing on the foot-lever X² the hooks on yoke U are drawn aside and the bucket lowered or dumped, as desired. From the foregoing it will be seen that the entire 25 movements of these mechanisms are under the immediate control and supervision of the operator on the car.

Having described my invention, I claim—

1. The combination of the motor-shaft, the

shafts arranged parallel therewith, the levers 30 I J, the links i j, and the pitman K, all arranged and adapted to operate substantially as set forth.

2. The combination of the car, the scale-beam hung thereon, the lever or bar V, connected to the scale-beam, the yoke hung on 35 said lever V, and the wedges mounted on the car and bearing on the yoke, as set forth.

3. The combination of the car, the scale-beam hung thereon, the lever or bar V, connected to the scale-beam, and the yoke hung 40 on said lever and adapted to support the bucket, as set forth.

4. In a machine for conveying and hoisting, the combination, with an open tram-car provided with an electric motor and a hoisting mechanism, substantially as described, of the bucket-holding mechanism consisting of the yoke U, suspended upon the end of lever V, fulcrumed to top of car-frame R, the bars T T, 45 having hooks t t, adapted to catch the projecting journals s s of sheave S, and the sheave Q², adapted to operate with the said hoisting mechanism, substantially as described.

EZRA NICHOLSON.

It is hereby certified that in Letters Patent No. 433,805, granted August 5, 1890, upon the application of Ezra Nicholson, of Cleveland, Ohio, the title of the invention was erroneously written and printed "Hoisting and Conveying Machines," whereas the said title should have been written and printed *Electric Hoisting and Conveying Machines*; and that the said Letters Patent should be read with this correction therein that the same may conform to the record of the case in the Patent Office.

Signed, countersigned, and sealed this 26th day of August, A. D. 1890.
